CIGARETTE-CASE.

1,140,305.

Specification of Letters Patent. Patented May 18, 1915.

Application filed May 25, 1914. Serial No. 840,943.

To all whom it may concern:

Be it known that we, SIDNEY HOLTZCLAW and DAVID H. GARNETT, citizens of the United States, residing, respectively, at 5 Kansas City, in the county of Wyandotte, State of Kansas, and Kansas City, county of Jackson and State of Missouri, have invented certain new and useful Improvements in Cigarette-Cases, of which the following is a specification.

This invention relates to pocket cigarette cases and our object is to provide a device of this character having a cigarette ejection opening, means for automatically dispensing the cigarettes in the box successively opposite said opening, and means whereby the cigarette opposite said opening may be projected partway through said opening so that it may be conveniently withdrawn 20 without the necessity of opening the case.

A further object is to produce a case of this character of simple, strong, durable, compact and cheap construction.

To these ends the invention consists in 25 certain novel and peculiar features of construction and organization as hereinafter described and claimed; and in order that it may be fully understood, reference is to be had to the accompanying drawing in 30 which:—

Figure 1, is a perspective view of a cigarette case embodying our invention. Fig. 2 is a horizontal section on the line II—II of Fig. 3. Fig. 3, is a central vertical section 35 of the case. Fig. 4, is a section taken on the line IV—IV of Fig. 1. Fig. 5, is a section taken on the line V—V of Fig. 1. Fig. 6, is a fragmentary perspective view of a modified construction of the bottom of the box 40 and of the cigarette presser plate.

In the said drawing, 1 is a shallow box, made preferably of sheet metal and for a short distance from its rear end its side walls are of increased height as at 2 and are 45 connected by a top piece 3, and one side wall is provided at the front end of part 2 thereof with a cigarette ejection opening 4, and the top 3 is provided near the opposite side of the case from opening 4 with a 50 longitudinal slot 5, occupying the same vertical plane as said opening 4 for a purpose which hereinafter appears.

The case is made complete by the use of a shallow flanged lid 6 which rests upon the 55 forward portion of the box and in conjunc-

tion therewith equals the depth of the rear portion of the box, so that the case as a whole shall be a shallow, smooth case and the corners will preferably be rounded so that it can be carried in a pocket without injury to the latter. The lid is hinged at 7 to the front edge of the top piece 3 of the case and a spring 8 of a type common in cigarette boxes and match boxes, is adapted for automatically opening the lid when the 60 thumb piece catch 9 is operated. This thumb piece catch is of common and well known construction, and is not detailed as it forms no part of applicants' invention, and the same is true with regard to the detailed 65 attachment of the spring 8, as applicants make no claim to such feature.

10 is a vertical partition which extends parallel with the rear wall of the case tangentially of the opening 4 and forms a stop 75 to position each cigarette opposite the ejection opening, this partition dividing the case into a narrow rear compartment 11 and the main or cigarette holding compartment 12.

To hold cigarettes, hereinafter identified by a reference character, down upon the bottom of the case so that they shall not fall out of the latter through careless handling of the case when the lid is open and also to 80 prevent any chance of the line of cigarettes buckling under the pressure imposed thereon by the presser plate, hereinafter identified, when the lid is open, there is provided a guard in the form of a strip 13, which 85 terminates at its rear end in a fork 14, the tines of which are bent to form eyes 15 fitting around the hinge rod or pintle 16. At its front end the guard is provided with a 90 depending catch 17 adapted to snap into a cavity 18 formed in the front wall of the case, the arrangement being such that when the lid is open, one may easily replace catch 17 to permit the guard to be swung up, so 95 that the case can be readily charged with 100 cigarettes.

19 is a hollow drum or cylinder arranged in compartment 11 and provided at one end with a trunnion 20 journaled in the adjacent side wall of the case. At its other end 105 the drum or cylinder is journaled on a pin 21 rigidly secured to the other side wall of the case, and arranged within the drum and secured at one end thereto and at the other end to a fixed pin 21 is a torsion 110

spring 22, the tendency of the spring being to rotate the drum in the direction indicated by the arrow, Fig. 3. For effecting an automatic feed of the cigarettes toward the partition 10, presser 23 preferably oval in cross section, is arranged in the case between the line of cigarettes and the front wall of the case, and said presser is connected by a tape 24 or its equivalent to the drum, the tape 10 underlying the line of cigarettes and extending through an opening 25 in the lower edge of the partition. It will thus be seen that when the case is to be fully charged with cigarettes the presser is drawn forward 15 and through the connection with the drum it tensions the spring 22 so that the latter will exert a constant pull on the presser and thus effect the feed of the line of cigarettes toward the partition each time a cigarette 20 is withdrawn through the ejection opening.

To effect the projection of a cigarette from the case so that the cigarette may be grasped and pulled out of the case, a feed mechanism 25 is provided, constructed as follows: 26 is a plate occupying the vertical plane of slot 5 and extending longitudinally thereof and normally closing the same and fitting against the underside of the top piece 3 so 30 as not to interfere with the positioning of a cigarette vertically below it, and said plate is provided with a rearwardly projecting arm 27 which projects through a shallow longitudinal recess 28 in the upper edge of partition 10 and is connected by a retractile spring 29 to a fixed lug 30, projecting from the partition 10. At the opposite end of plate 26 from arm 27 is a depending finger 31 to abut against one end of the cigarette 35 bearing against the partition 10, and secured to plate 26 and extending downward through slot 5 is the shank 33 of a flat finger piece 32 upon which the operator will place his finger or thumb for the purpose of sliding said finger piece along the slot and thus, 40 through the pressure of the finger 31 forcing the cigarette in its path from the position shown in Fig. 2 to the position shown in Fig. 1, after which it may be grasped and withdrawn from the case.

In Fig. 6 the bottom of the case is provided with a channel 34 wherein fits slidingly one horizontal arm 36 of a presser 35, corresponding in function to presser 23, and 55 said presser 35 will be drawn rearwardly to effect the feed of the cigarettes by connecting arm 36 with the spring actuated drum through the medium of a flexible cord 37, the cord corresponding in function to the 60 tape 24.

From the above description it will be apparent that we have produced a cigarette case embodying the features of advantage enumerated as desirable and which is obviously susceptible of modification as regards

its form, proportion, detailed construction and arrangement, without departing from the principle of construction involved or the spirit and scope of the appended claims.

We claim:—

1. A shallow case, provided with an opening in one side wall thereof, a hinged lid for the case, a yieldingly actuated presser for engaging and moving sidewise within the case one or more cigarettes until the cigarette or cigarettes are successively alined with said opening, and a guard interposed between the lid and the cigarette or cigarettes whereby to retain the same in position in the case when the lid is open. 70

2. A shallow cigarette case comprising a body and a lid, the former being provided with an ejection opening in one side, a partition within and extending parallel with cigarettes in the body of the case and adjacent the rear margin of said opening, a presser in the body paralleling said partition, yielding means for causing said presser to press one cigarette or a line of cigarettes laterally until arrested by said partition, 80 and a guard overlying the cigarette or cigarettes in and carried by said body to retain the cigarettes in position when the lid is open. 85

3. A shallow cigarette case comprising a body and a lid, the former being provided with an ejection opening in one side, a partition within and extending parallel with cigarettes in the body of the case and adjacent the rear margin of said opening, a 90 presser in the case paralleling said partition, yielding means for causing said presser to press one cigarette or a line of cigarettes laterally until arrested by said partition, and a guard overlying the cigarette or cigarettes in and carried by said body to retain the cigarettes in position when the lid is open, said guard being hinged to the body at one end and detachably engaging it at the other end. 105

4. A shallow cigarette case provided in one side wall with a cigarette ejection opening, a partition dividing the case into two compartments and located tangentially of the rear margin of said opening and provided with an opening adjacent the bottom of the body, a spring actuated drum in the compartment partition from said opening, a presser arranged in the other compartment and extending parallel with said partition, 115 and a flexible connection extending through the opening of the partition and along the bottom of the case between the drum and the presser for causing the latter to press one or more cigarettes sidewise until arrested by 120 said partition.

5. A shallow cigarette case provided in one side wall with a cigarette ejection opening, a partition dividing the case into two compartments and located tangentially 130

of the rear margin of said opening, a spring actuated drum in the compartment located back of said partition, a presser arranged in the other compartment and extending 5 parallel with said partition, a flexible connection between the drum and the presser for causing the latter to press one or more cigarettes sidewise until arrested by said partition, and means for applying endwise 10 pressure on the cigarette in contact with said partition to project said cigarette through the said opening.

6. A shallow casing comprising a body of increased depth at its rear end and provided 15 at such end with a fixed top having a transverse slot and also provided at such end with an opening in one of its side walls, a transverse partition in the rear end of the case in a vertical plane rearward of said opening, a guard paralleling the bottom of the 20 case and hinged at its rear end to the front

edge of the top and detachably connected at its front end to the case, a hinged lid for the shallow portion of the case, a spring actuated drum journaled in the case behind 25 the partition, a presser in the case below the guard, a flexible connection wound on the drum and leading along the bottom of the case to the presser, to cause the latter to move a cigarette or other object sidewise 30 within the case until arrested by the said partition, and means extending slidably through said slot for applying endwise pressure on the cigarette or other object to project it part way through the said opening. 35

In testimony whereof, we affix our signatures, in the presence of two witnesses.
